United States Patent Office

Des. 227,560

Patented July 3, 1973

227,560

BUILDING

Paul J. Marks, Towson, Gilbert D. Cooke, Columbia, and Willard J. Schroll and James E. Van Noy, Jessup, Md., assignors to Better Marketing Industries, Inc.

Filed Nov. 5, 1971, Ser. No. 196,264

Term of patent 14 years

Int. Cl. D25—03

U.S. Cl. D13—1 A

FIG. 3

FIG. 1 is a perspective view of a building embodying our design as seen from above the front right hand side thereof;

FIG. 2 is a front elevational view of the building;

FIG. 3 is an elevational view of the building as seen from the right hand side thereof;

FIG. 4 is a rear elevational view of the building; and

FIG. 5 is an elevational view of the building as seen from the left hand side thereof.

We claim:

The ornamental design for a building, substantially as shown.
